HARROW

Leo U. Burkes, Richton, Miss.

Application December 30, 1936, Serial No. 118,415

5 Claims. (Cl. 55—154)

This invention relates to soil conditioning and cultivating machines and has reference in particular to what may well be called a convertible type harrow, that is, one which may have its multiple spring teeth arranged to function as a customary V-shaped style, or may have the teeth obliquely angled with respect to the line of draft to perform as a so-called side harrow.

Structurally visualized and compared with prior art harrow constructions, it will be observed that the adopted harrow is characterized by a frame unit, a beam intersecting and adjustably connected to the central portion of the frame unit, bracing means for the beam, and steering 10 and manipulating handles for the walking attendant, there being a plurality of spring teeth connected with and dragging behind said frame underneath of the handle. This general structural arrangement is, of course, common to the 15 trade and it is also a matter of common knowledge that quick detachable and adjustable spring teeth are provided for conversion results.

The essence of the present invention is reflected in the adoption and use of a substantially rectangular frame unit provided with a plurality of improved bodily adjustable clamps so constructed as to serve as stirrup-like hangers for the shank portions of the spring teeth, the clamps and frame unit being so constructed as to permit the 20 teeth to be disposed at direct right angles to the frame unit for individually or collectively adjusting to assume substantially oblique angled position with respect to said frame unit.

Stated more specifically, the chief novelty resides in the provision of a frame unit characterized by spaced parallel bar members having their lower edges formed with keeper notches to selectively accommodate distinguishably usable retention lugs on the block-like adapter forming part 25 of the clamping means, said adapter being saddled in the hanger stirrup or fixture which is, in turn, secured by set screw or the like to associated retaining means cooperable with the bars of said frame unit.

Although novelty is predicated on the notched bar construction of the frame unit as well as the stirrup-like hanger members, the specific novelty in chief has to do with the multiple lug-equipped block-like adapter which is in effect the holder 30 for the shank portion of the associated detachable spring tooth.

Other features and advantages will become more readily apparent from the following description and drawings.

55 In the accompanying drawings wherein like

numerals are employed to designate like parts throughout the various views:—

Figure 1 is a top plan view of the complete multiple purpose or convertible harrow constructed in accordance with the principles of the present invention showing the old as well as the new features. 5

Figure 2 is a side elevational view of the rear end portion of the arrangement depicted in Figure 1 calculated to show to advantage the general relationship of the horizontal beam with respect to the spring teeth and improved holding means therefor. 10

Figure 3 is a bottom plan view of the rectangular frame unit showing the two distinguishable 15 positions of the adapter blocks, the stirrup clamping means being omitted for clearness of illustration, one block being disposed at right angles and the other at oblique angles.

Figure 4 is a top plan view of one end portion 20 of Figure 3, that is, a view observing the right hand end portion of Figure 3 with certain of the other features omitted for clearness of illustration of parts.

Figure 5 is what may be called a full size view 25 of one of the multiple lug-equipped adapter blocks or members.

Figure 6 is a section taken on the plane of the line 6—6 of Figure 1.

Figures 7, 8 and 9 are additional sectional 30 views, on an enlarged scale, taken on the planes of the lines 7—7, 8—8 and 9—9, respectively, of Figure 1.

Reference is had first to the general assemblage depicted in Figure 1 of the drawings. Here the 35 spring teeth are denoted by the numeral 10 and have downturned hooked ground-engaging ends 11 as shown in Figure 2. This is, normally speaking, a five-tooth harrow and the forward ends or shank portions of the teeth 10 are adjustably 40 clamped in holders carried by the aforementioned rectangular frame unit 12. The numeral 13 designates the brace while the numeral 14 indicates the beam to the forward end of which the source of propulsive power is connected. The customary attendant-controlled handles 15 are shown at the rear. The intermediate portion of the beam intersects the central portion of the frame unit 12 and is adjustably attached to the slotted extension or flange 16 as indicated at the 45 point 17.

Reference being had now to Figure 3 it will be observed that the ever important frame unit 12 is of general rectangular or longitudinally elongated form and includes spaced parallel sup- 50 55

porting bars or members 18 having keeper notches 19 and 20 formed in the lower surfaces or edges thereof and arranged in diagonal staggered relationship.

The adapter block is denoted by the numeral 21 and is of general rectangular form. As shown to advantage in Figure 3 the bottom of the block is formed with a channel 22 in which the shank of the tooth fits slidably so that the tooth can be adjusted to position the hook or tooth element 11 toward or from the frame 12. It will be noticed in Figure 5 that one end, that is, the rear end of the block is indicated by the numeral 23, while the diagonally cut or oblique forward end 15 is differentiated by the numeral 24. A pair of transverse spaced parallel stabilizing cleats 25 are provided on the attaching side of the block, one of the cleats being close to the rear end 23 and the other one at the center of the block and 20 both cleats being parallel to each other and parallel to said edge 23. Cooperable with these cleats are pairs of lugs 26 extending at obtuse angles in relation to the transverse cleats 25. The effect of these two sets of lugs 26, which function as teeth, 25 is that said lugs are substantially oblique to the longitudinal dimension of the block 21 as a unit. The numeral 27 designates supplementary cleats disposed parallel to each other and in parallelism with the correspondingly inclined or oblique edge 24. A group of three teeth or lugs 28 cooperate with these cleats 27. It follows that the teeth 26, 30 that is, both sets, and the cleats 25 function simultaneously. These are used alternately with respect to the cleats 27 and their associated properly angled teeth 28. The teeth or lugs 28 by the 35 way are substantially straight with respect to the longitudinal dimension of the block 21. The gist of the idea, however, is to be able to use the selected sets of teeth with respect to predetermined keeper notches 19 and 20 in the bars 18 as shown in Figure 3 to get the desired predetermined angular position of the adapter block 21 with respect to said bars 18. For example, in 40 Figure 3 at the right it will be noticed that the teeth or lugs 26 are then engaged with the keeper notches 19 and 20. This positions the edge 23 flush with the bars 18, disposes the cleats 25 in contact with the inner surfaces of the bars 18 as shown in Figure 4, and positions the block 21 as 45 a unit, at right angles to the longitudinal dimension of the frame unit 12. It follows that when the adapter block is in this position the shank portions of the teeth 10 are at right angles to said frame unit 12. Then by shifting the block 50 21 the teeth 28 may be engaged with the notches 19 and 20 at which time the oblique edge 24 matches the bar 18, positioning said adapter block 21 diagonally and throwing the teeth 10 in the same diagonal position with respect to the 55 frame unit 12.

is clamped firmly down on the upper edges of the bars 18. At the same time it binds the selected lugs 26 or 28 in the keeper notches 19 and 20. It also effectively binds the shank of the tooth in the channel 22 thus providing the desired holder or clamping means for the tooth. It follows, therefore, that the holder comprises the adapter block 21 adjustably connectible by its teeth 26 and 28 to the keeper notches 19 and 20 through the instrumentality of the set screw clamping means 29. By using the simple hanger clip or suspension element 30 and the set screw 31 and frame hanger 29, the feature 29 can be axially adjusted in conjunction with the toothed block or adapter 21 to satisfactorily obtain either of the two set positions shown in full lines in Figure 3.

It follows that with this adjustable tooth clamping or holder means it is possible to properly arrange the teeth 10 to function either as the conventional V-shaped harrow or angled with respect to the line of draft to serve as a so-called side harrow.

Attention is invited to Figure 2 wherein it will be observed that the numeral 32 designates an arm adjustably mounted by a so-called rosette clamp 33 on one end of the frame 12. This arm carries a blade 34 which constitutes a dirt shield located between two of the spring teeth to facilitate the operation of the teeth and to guard against easy breakage of these fragile spring teeth. 25 30

It is thought that the description taken in connection with the drawings will enable a clear understanding of the invention to be had. Therefore, a more lengthy description is thought unnecessary. 35

While the preferred embodiment of the invention has been shown and described, it is to be understood that minor changes coming within the field of invention claimed may be resorted to if desired. 40

What is claimed is:—

1. In a structure assemblage of the class described, a frame unit including a pair of spaced parallel bar members, a clip resting on the upper edges of said members, a hanger stirrup embracing and hung from said clip and located between said bar members, a set screw adjusting and clamping connection between the clip and hanger stirrup, and adapter means in said hanger stirrup serving to slidably receive the shank portion of a cooperating spring harrow tooth. 45 50

2. In a structure of the class described, a relatively stationary frame unit of general rectangular form including spaced parallel bar members, a stirrup-like hanger and clamping member disposed between said bar members, a clip resting on the upper edges of the bar members, said hanger member being attached thereto through the instrumentality of a set screw, an adapter block saddled in said hanger member, said adapter block being grooved to slidably accommodate the shank portion of a cooperating spring harrow tooth, and co-acting elements between the lower edges of the bar members and adjacent surface of the adapter block to permit said block to be arranged either at right angles or oblique angles to properly position the harrow tooth as described. 65 60 65

3. In a structure of the class described, a frame unit including spaced parallel bar members having keeper notches formed in their lower edge portions, an adapter block having selectively usable sets of teeth engageable with the keeper notches, said adapter block having its underside 75

- grooved to slidably receive the shank portion of a complementary harrow tooth, a hanger element embracing the adapter block and located between the bar members of said frame unit, and means for clamping the hanger member firmly on said frame unit in the manner and for the purposes described.
4. In a structure of the class described, a rectangular relatively stationary frame unit including spaced parallel bar members having diagonal keeper notches formed in their lower edges, an adapter block, said adapter block being provided with spaced sets of distinguishable lugs and said sets of lugs being selectively engageable with said keeper notches to permit the block to be disposed either at right angles to the longitudinal dimension of the frame unit or in a position sub-
- stantially oblique to said longitudinal dimension, and means for clamping the adapter block firmly in the notches, said means being cooperable with the bar members of the frame unit.
5. As a new article of manufacture, a component part of an assemblage of the class described, comprising a frame unit including spaced parallel bar members having selectively usable keeper notches, an adapter unit having selectively usable keeper lugs engageable with said notches to allow the unit to be connected with the frame in a position to dispose it at right angles or obliquely to the longitudinal dimension of said frame, said adapter unit being grooved to accommodate the shank of a harrow tooth. 15
